Primary Examiner — Ricky Pham(74) *Attorney, Agent, or Firm* — John S. Artz; Dickinson Wright PLLC(57) **CLAIM**

The ornamental design for a crank assembly, substantially as shown as described.

DESCRIPTION

FIG. 1 is a front elevated isometric view of my design;

FIG. 2 is a rear bottom isometric view of my design;

FIG. 3 is a front side view of my design;

FIG. 4 is a rear side view of my design;

FIG. 5 is a right side view of my design;

FIG. 6 is a left side view of my design;

FIG. 7 is a top view of my design; and,

FIG. 8 is a bottom view of my design.

The broken lines shown in the drawings are included for the purpose of illustrating an environmental structure and form no part of the claimed design.

1 Claim, 8 Drawing Sheets(56)
